(57) **CLAIM**

The ornamental design for fishing tackle tray box carrier as shown and described.

DESCRIPTION

FIG. 1 is a perspective view of a front side of a fishing tackle tray box carrier showing our new design.

FIG. 2 is a perspective view of a bottom side thereof.

FIG. 3 is an elevational view of the front side thereof, which is a mirror image of an opposing, back side thereof.

FIG. 4 is an elevational view of a first lateral side thereof, which is a mirror image of an opposing, second lateral side thereof; and,

FIG. 5 is a perspective view of the front side thereof showing fishing tackle tray boxes contained within the fishing tackle tray box carrier.

The broken lines illustrating features of the fishing tackle tray box carrier represent unclaimed portions of the design. The broken lines illustrating fishing tackle tray boxes in FIG. 5 represent environment of the claimed and form no part of the claimed design.
